UNITED STATES PATENT OFFICE.

ALPIN M. BOWES, OF DENVER, COLORADO.

COMBINED SAW, SQUARE, AND BEVEL.

No. 823,101.

Specification of Letters Patent.

Patented June 12, 1906.

Application filed December 26, 1903. Serial No. 186,709.

To all whom it may concern:

Be it known that I, ALPIN M. BOWES, a citizen of the United States of America, residing in the city and county of Denver and State of Colorado, have invented certain new and useful Improvements in a Combined Saw, Square, and Bevel; and I do declare the following to be a full, clear, and exact description of the invention, such as will enable others skilled in the art to which it appertains to make and use the same, reference being had to the accompanying drawings, and to the letters of reference marked thereon, which form a part of this specification.

My invention relates to a saw provided with square and bevel attachments, whereby the saw may be used as a square or bevel without interfering in any way with its ordinary or sawing function.

The novel features of my improvement are connected with the handle of the saw, the edge of the latter remote from its toothed or cutting edge being graduated to coöperate with the features of my improved attachment.

Having briefly outlined my improved construction, as well as the function it is intended to perform, I will proceed to describe the same in detail, reference being made to the accompanying drawings, in which is illustrated an embodiment thereof.

In the drawings, Figure 1 is an elevation of the saw equipped with my improvements, the handle of the saw being shown partly in section on the line 1 1, Fig. 3. Fig. 2 is an edge view of the same looking in the direction of the upper edge of the saw or the edge remote from its toothed edge. Fig. 3 is a section taken on the line 3 3, Fig. 1. Fig. 4 is an elevation of the device looking at the opposite side from that shown in Fig. 1.

The same reference characters indicate the same parts in all the views.

Let A designate the ordinary saw-blade, except that its upper or plain edge is graduated, as shown at A'. The handle B of the saw is attached to the blade by means of screws B⁶, and in this handle on one side of the saw is formed a pocket in which a slotted, 50 arm C, having a beveled extremity C', is located. This part C, I will term a "bevel." In the saw-handle near the upper edge of the saw-blade and passing through the latter where it enters the handle is located a thumb-screw D, which also passes through the slot C² of the bevel. By means of this thumb-

screw the bevel may be locked in any desired position of adjustment. By loosening the thumb-screw the bevel may be drawn out of its pocket and thrown to either of the dotted-line positions indicated in Fig. 1 or any other desired position from a position at right angles to the edge A' of the saw-blade to any degree of obtuse or acute angle. The rear part of the handle on one side of the saw consists of a graduated shoulder B', forming a straight edge adapted to coöperate with the edge A' of the saw-blade to form a square or perform the function of the ordinary carpenter's tool known by that name. This straight edge B' is located somewhat in the rear of the bevel, while on the opposite side of the saw the rear part of the handle is provided with a straight edge or shoulder B², which is in line with the rear edge C³ of the bevel. Thus when the shoulder B² is placed against a part, the saw being in the position shown in Fig. 1, if the bevel be drawn out of its pocket the user of the saw will know that its edge C³ is in line with the straight edge B² on the opposite side of the saw, and by throwing the bevel in either direction after it is withdrawn from its pocket a line may be drawn at any desired angle to the straight-edge shoulder B², and consequently to any desired angle to a part against which the shoulder B² abuts.

As is well known, the body of the ordinary saw-handle is composed chiefly of wood. In order that the set-screw may be properly operated, it is found necessary to insert in a recess formed in the handle of the saw a metal bushing E to receive the threaded part D' of the thumb-screw. This bushing is secured to the handle by means of suitable fastening devices E'. (See Fig. 4.) Also in order to have the straight edge B' of proper construction a metal piece (distinctly shown in Fig. 3) is employed for this purpose. This part B' is angle-shaped in cross-section, and its graduated face projects outwardly from the blade of the saw and occupies a position in the rear of the part D² of the saw-handle and is held in place by screws D³.

When the device is in use, it may be assumed in the first instance that the bevel C is pocketed or shoved entirely into the recess formed for it in the saw-handle and held securely in place by the thumb-screw D. The saw is then used in the ordinary way. When the bevel is pocketed, the saw may also be used as a square by utilizing the graduated

straight edge B' in connection with the graduated edge A' of the saw. The shoulder B² may also be used in connection with the projecting part of the bevel. When, however, it is desired to draw a line of some length at right angles to the edge A' of the saw or to draw a line at any other degree of angle to either the edge A' of the saw or the straight edge B² of the handle, the thumb-screw D may be loosened, the bevel drawn out to its limit of movement, after which it may be adjusted to occupy any desired position and then held in this position by means of the setscrew, which is tightened for the purpose. By reference to Fig. 1 of the drawings it will be seen that the walls of the pocket in which the bevel is located are cut away at the mouth of the pocket, forming shoulders B³ and B⁴ to allow the bevel to be thrown to either extreme position indicated by dotted lines in Fig. 1 or to any desired intermediate position.

Having thus described my invention, what I claim is—

- 25 1. A combined saw and bevel consisting of a saw having a handle in which is formed a pocket on one side of the blade, a bevel slideable in said pocket, the latter being closed except at one end where the bevel protrudes, and suitable means for locking the bevel in any desired position of adjustment.
- 30 2. The combination with a saw, of a bevel, the handle of the saw being provided on one side with a pocket in which the bevel is slideable, the pocket being closed except at one end where the bevel protrudes, and suitable

means for locking the bevel in any desired position of adjustment, the handle of the saw on one side of the blade being provided with a shoulder forming a straight edge lying 40 in the same plane with the edge of the bevel, when pocketed or extended therefrom in a straight line.

3. The combination of a saw provided with a blade having a straight edge and a handle 45 provided on one side with a straight edge extending at right angles to the straight edge of the saw-blade, the handle being provided with a pocket closed except at the end adjacent the straight edge of the blade, and a 50 bevel located in said pocket and having one of its edges in the same plane with a shoulder formed on the opposite side of the blade from the bevel-pocket.

4. The combination of a saw provided with 55 a blade having one straight edge and a handle provided with a pocket closed except at one end, the open end of the pocket being adjacent the straight edge of the blade, a bevel located in said pocket and adjustable longitudinally therein, the mouth of the pocket adjacent the straight edge of the blade being cut away on opposite sides to allow the bevel to swing in either direction to form angles 60 with the straight edge of the blade. 65

In testimony whereof I affix my signature in presence of two witnesses.

ALPIN M. BOWES.
